CIGARETTE ROLLING DEVICE

Nicolay K. Fougner, New York, N. Y.

Application January 12, 1933, Serial No. 651,412

6 Claims. (Cl. 131—5)

This invention relates to devices for rolling cigarettes and aims to provide an extremely simple but highly efficient device, by virtue of which anyone without possessing any extraordinary degree of skill or previous experience is enable to expeditiously produce cigarettes.

The invention further comprehends a device which may be so inexpensively produced that it may be made as an adjunct to and incorporated in a package of cigarette papers or a container of tobacco as a part thereof, whereby it may be discarded when the supply of papers or tobacco is exhausted, it being understood that if desired, the device may be more elaborately and expensively made as an article separate from such packages or containers and of such value as to be preserved for a considerable length of time.

With these and other objects in view, reference is made to the following specification and accompanying drawing, in which there is set forth a preferred embodiment of the invention, while the claims define the actual scope thereof.

In the drawing:

Figure 1 is an outer or lower face view of the rolling device incorporated in a package of cigarette papers and showing the device extended.

Figure 2 is a side view thereof.

Figure 3 is an inner or upper face view with a part of the cigarette package broken away and shown in section, and illustrating the cigarette paper and tobacco positioned thereon for the initial step in rolling the cigarette.

Figure 4 is a fragmentary plan view illustrating the manner in which the cigarette is rolled.

Figure 5 is an enlarged fragmentary side edge view illustrating what may be termed the final step in the rolling of the cigarette.

Figure 6 is a face view illustrating the rolling device extended around and covering the cigarette paper package.

Figure 7 is a side edge view therof.

Referring to the drawing by characters of reference, A designates generally a cigarette paper package of a standard type which consists of a carton or casing 10, in which the cigarette papers 11 are arranged and from which they are withdrawn through slots 12 formed in the carton or casing.

The rolling device which constitutes the present invention is generally designated by the reference character B, and while said device is shown as incorporated in and forming a part of the cigarette paper package A, it is to be understood that this only constitutes one manner of reducing the invention to practice, as it is clearly evident that

within the scope of the invention the rolling device may be made as a separate entity. In its preferred form, the rolling device as disclosed consists of a sheet of flexible material 15 of a width corresponding approximately to the length of a standard cigarette and of a length exceeding the same. In the concept of the invention illustrated, where the rolling device is incorporated in and forms part of a cigarette paper package, one end 16 of the sheet 15 is secured to the package 60 carton or casing 10 in any suitable manner, while the remaining portion of the sheet extends outwardly beyond one side edge of said casing or carton. Adjacent the free or unsecured end thereof, the sheet 15 is so fashioned as to render the same 65 rigid in the direction of its width and flexible in the direction of its length. This may be accomplished in various ways, but for the purpose of the present disclosure a plurality of spaced parallel ribs 17 is applied to the outer or lower surface, 70 covering a predetermined area defined by the outer free edge 18 and between the side edges 19 of the sheet 15, said ribs terminating at a point spaced from the edge of the cigarette paper casing or carton from which the sheet 15 protrudes. 75 This leaves a blank flexible area a which may be utilized for the purpose of printing or otherwise applying thereto advertising matter or directions for using the rolling device. At the free end edge 18 of the sheet 15, there is provided at least one 80 protruding tab 20, in the present instance one being shown disposed transversely medial of the sheet 15, and said tab having on the outer or lower surface the ribs 17.

In use and operation, the surface x of the sheet 15 is disposed uppermost, as shown in Figure 3, and a cigarette paper 11 is positioned thereon with one longitudinal edge located to substantially coincide with the outer free end edge 18 of the sheet 15. If the cigarette paper is of 90 the type having a gummed edge 13 as illustrated, the gummed edge is disposed upwardly and said gummed edge is arranged away from the outer end edge 18, as shown in Figure 3. The tobacco t of an appropriate quantity is then laid on the 95 paper adjacent the outer ungummed edge. While holding and supporting the device with the second fingers i and the thumbs j, the two index fingers k are employed to evenly distribute the tobacco and the outer end of the sheet 15, together with the cigarette paper, is folded over the tobacco in the manner shown in Figure 4. After several preparatory operations of moving the turned over portion of the sheet 15 forwardly and rearwardly between the thumbs 100 110

j and the index fingers *k*, the gummed or inner edge 13 is moistened and the turned over edge of the sheet is then advanced forwardly, wrapping the outer edge of the cigarette paper around the tobacco, as clearly illustrated in Figure 5. At this point, the tab 20 bears against the cigarette paper, slides thereover, and causes the free edge of the sheet to also slide over the cigarette paper and functions to prevent the cigarette paper from wrapping around the outside of the sheet, as the tab directs the said edge 18 forwardly while the outer edge of the paper rolls inside of the gummed edge 13. The continued forward movement of the inturned edge of the sheet 15 will finally accomplish the complete wrapping of the paper around the tobacco *t* and the moistened gummed edge will adhere thereto, completing the rolling operation.

20 The upper or inner surface *x* of the sheet 15 is of sufficient character to prevent slippage of the cigarette paper thereon while the outer or lower ribbed surface will give the necessary traction to the fingers in accomplishing the rolling operations previously described.

25 The tab 20 in addition to performing the function stated may serve the secondary purpose of retaining the device in closed relation embracing the cigarette paper casing or carton 10 by inserting the same within one of the slots 12, as clearly illustrated in Figures 6 and 7.

30 A package of cigarette paper, constituting a fixed part and located at one end of the wrapping sheet, serves as a weight to hold this end of the sheet downwardly and prevents it from rolling upwardly while the other end of the sheet is being manipulated to roll a cigarette.

35 While there has been illustrated and described a preferred embodiment of the invention, no limitation is intended to the precise structural details set forth, as variations and modifications thereof which fall within the scope of the appended claims may be resorted to when desired.

What is claimed is:

40 45 1. A cigarette rolling device comprising a flex-

70

ible sheet, and a cigarette paper engaging tab on the free end of the sheet narrower than the sheet.

2. A cigarette rolling device comprising a flexible sheet, and a cigarette paper engaging tab on the free end of the sheet narrower than the sheet, said tab located centrally of the sheet.

3. A cigarette rolling device comprising a flexible sheet, a cigarette paper engaging tab on the free end of the sheet narrower than the sheet, and ribs fixed to the back of the sheet and tab, said ribs stiffening the sheet and tab laterally and permitting flexibility longitudinally of the tab and sheet.

4. A cigarette rolling device comprising a flexible sheet, a cigarette paper engaging tab on the free end of the sheet narrower than the sheet, said tab located centrally of the sheet, and ribs fixed to the back of the sheet and tab, said ribs stiffening the sheet laterally and permitting flexibility longitudinally of the tab and sheet.

5. A cigarette rolling device comprising a sheet flexible longitudinally and rigid laterally or transversely, a cigarette paper engaging tab fixed to one end of the sheet, and a cigarette paper package fixed to the other end of the sheet, said package so arranged as to permit a sheet of cigarette paper to be drawn therefrom directly onto the surface of the sheet to receive tobacco to be rolled into a cigarette.

6. A cigarette rolling device comprising a sheet flexible longitudinally and rigid transversely, said sheet adapted to receive a cigarette paper with tobacco thereon and adapted, when grasped adjacent its end portions between the thumb and fingers of the hands, to roll the cigarette paper around the tobacco and within the sheet, and a cigarette paper-engaging tab at the intermediate portion and at the free end of the sheet adapted to engage the cigarette paper and prevent it from winding or wrapping around the outside of the flexible sheet while the latter is rolling the cigarette.
